A. WURDACK

CHAIR

Filed August 18, 1924

Inventor

Arthur Wurdack

Arthur Wurdock
By Cornwall, Radell & James. Atts.

UNITED STATES PATENT OFFICE.

ARTHUR WURDACK, OF NORMANDY, MISSOURI.

CHAIR.

Application filed August 18, 1924. Serial No. 732,655.

To all whom it may concern:

Be it known that I, ARTHUR WURDACK, a citizen of the United States, residing at Normandy, St. Louis County, Missouri, have invented a certain new and useful Improvement in Chairs, of which the following is a specification, such as will enable others skilled in the art to which it appertains to make and use the same.

10 My invention relates to furniture and consists in an improved chair or rocker construction.

The object of my invention is to provide a simple economical chair having a yielding back, to provide a chair which may be easily assembled and disassembled for shipping or storing, and to provide a chair which may be used outdoors as well as indoors without deterioration due to the weather.

20 In the accompanying drawings which illustrate my invention—

Figure 1 is a side elevation of my improved chair, the dot and dash lines indicating the modification of the chair to produce a rocker.

Figure 2 is a rear elevation of the same.

Figure 3 is a vertical section on line 3—3 of Figure 2.

Figure 4 is a horizontal section on line 30 4—4 of Figure 2.

Figure 5 is a rear elevation corresponding to Figure 2 but showing a modified construction.

The chair comprises four straight legs, 35 preferably disposed vertically, the rear legs being indicated at 1 and the front legs at 2. A rear rail 3 connects the rear legs 1, a front rail 4 connects the front legs 2, and side rails 5 connect a front and a rear leg 40 on each side of the chair, respectively. The chair seat is formed by one or more boards 6 extending across opposite rails. All of the parts mentioned are rectangular in shape to facilitate their preparation and assembly, the legs being gained near their upper ends to receive rails and form a better joint.

50 Spaced below each rail is a rung connecting the legs, the rear rung being indicated at 7, the side rungs at 8 and the front rung at 9.

55 My invention consists particularly in the back and its application to the chair. In the preferred form, the back consists in a single board 10 thin enough to be flexible, to a limited extent, when under pressure

from the back of a person sitting upon the chair. The width of the board is preferably the same as the distance between the rear legs 1 and the board extends down below the seat a substantial distance and is so inclined that it extends between these rear legs and braces them transversely of the chair. The lower end of the board is secured to rear rung 7 by means of bolts 11 60 and near the chair seat the back is secured to rear rail 3 by means of bolts 12. The projection of rail 3 to the rear of rung 7 and the still further rearward projection of seat 6 provides means for inclining the 70 back forming board as shown. By tightening bolts 12, board 10 is drawn against the rear edge of seat 6 and the extended bearing of the seat edge and the back forms a pivot about which the back may bend as indicated in Figure 3 and lessens the likelihood of splitting of the board under pressure. 75

In use, the back described affords a firm yet yielding support for substantially the 80 entire surface of the back of the user and affords a degree of comfort not present heretofore in chairs made of solid wood without cushions or panels of leather, fabric, cane or the like.

By removing bolts 11 and 12, the back and lower portion of the chair are easily disassembled, thus facilitating packing and shipping.

While I have illustrated the single board 90 10 as the preferred back construction, similar results will be obtained, and possibly costs will be lowered, by the use of a back formed of a plurality of strips, such as indicated in Figure 5, in which the strips 13 are shown connected near their lower end by a cross piece 14 and near their upper end by a cross piece 15. If desired a cross piece 16 may be provided adjacent to the back rail 17 to receive the bolts 18 and distribute the 100 bolt pressure to the strips 13.

Obviously, the cross pieces 14, 15 and 16 may be omitted and a bolt provided for each strip at the rung 19 and at rail 17.

Other modifications of my invention will 105 suggest themselves in the manufacture of my improved chair and I contemplate such variations as are included in the scope of the following claims.

I claim:

1. In a chair a seat, front and rear legs supporting said seat, a rear rail rigidly con-

nected with the rear legs below said seat, a rung connected with said rear legs in front of the plane of said rail, and an upwardly and rearwardly inclined back member having its lower portion attached to said rung and its intermediate portion attached to said rail.

2. In a chair a seat, front and rear legs supporting said seat, a rear rail rigidly connected with the rear legs below said seat, a rung connected with said rear legs in front of the plane of said rail, and a flexible back member having its lower portion attached to said rung and its intermediate portion attached to said rail, said back member extending above the seat and inclining upwardly and rearwardly therefrom.

3. In a chair, a seat, front and rear legs, a rung and a rail spaced from each other and extending between said rear legs, and a flexible wooden unit detachably secured to said rung and rail abutting the inside faces of the rear legs at its edges thereby forming a transverse brace and extending above the level of said seat to form a yielding back for the chair.

4. In a chair, a seat, a back extending from below said seat to above the level of said seat and consisting in a single substantially straight flexible board secured at close intervals near said seat and at a point below said seat and unsecured above said seat so as to bend about the rear edge of the seat as a pivot.

35 5. In a chair, a seat, spaced rear legs supporting said seat, and a single flexible board secured adjacent to said seat, the lower por-

tion of which board extends between and braces said legs and the upper portion of which board projects above the level of said seat and forms a yielding back for the chair.

6. In a chair, a seat, rear legs, a rail beneath said seat and connecting said legs, a rung below said rail and spaced therefrom and connecting said legs, and a back consisting of a flexible board secured to said rung and to said rail and extending upwardly therefrom above said seat and unsecured above said rail.

7. In a chair, rear legs, a rung between said legs, a rear rail at the top of said legs and projecting rearwardly thereof, a seat above said rail projecting rearwardly thereof, and a flexible back-forming board the lower portion of which is held rigid by being secured to said rung and rail and the upper portion of which is positioned by the rung and rail and the rear edge of said seat so as to incline rearwardly above the level of said seat.

8. In a chair, rear legs, a rung between said legs and below the tops thereof, a seat projecting rearwardly of said legs, a flexible board secured to said rung extending upwardly therefrom and forming a back for the chair, a rear rail at the tops of said legs in front of the rear edge of said seat, and means drawing said board against the lower edge of said rail and against the rear edge of said seat.

In testimony whereof I hereunto affix my signature this 12th day of August, 1924.

ARTHUR WURDACK.
